UNITED STATES PATENT OFFICE.

ALFRED T. STEVENS, OF FERRY, MICHIGAN.

RAILROAD TIE AND CHAIR.

SPECIFICATION forming part of Letters Patent No. 351,002, dated October 19, 1886.

Application filed April 26, 1886. Serial No. 200,195. (No model.)

To all whom it may concern:

Be it known that I, ALFRED T. STEVENS, a citizen of the United States, residing at Ferry, in the county of Oceana and State of Michigan, 5 have invented a new and useful Improvement in Railroad Ties and Chairs, of which the following is a specification.

My invention relates to an improvement in railway ties and chairs; and it consists in the 10 peculiar construction and combination of devices, that will be more fully set forth herein-after, and particularly pointed out in the claims.

In the drawings, Figure 1 is a perspective 15 view of a railway tie and chair embodying my improvements. Fig. 2 is a vertical longitudinal sectional view of the same. Fig. 3 is a vertical transverse sectional view of the same, taken on the line $x-x$ of Fig. 2.

20 A represents a railway-tie, which is made of either cast or wrought metal, and is provided on its upper side with laterally-extending flanges B.

D represents a pair of plates, which are bent, 25 as at d and d' , so as to form the outwardly-extending bases or plates d^2 , which bear upon the tie, the inclined lips D' , to embrace the base of the rail, and the vertical plates D^2 , to bear against opposite sides of the rail, between 30 the base and the head thereof. The said plates D thus constitute a chair, to effect the double purpose of securing the meeting ends of rails together and make a secure joint, and also to secure the rails firmly to the tie. The ends of

35 the plates d^2 are bent under, and are thereby adapted to engage the laterally-projecting flanges B of the tie. The bent ends of the plates d^2 form catches or hooks d^3 . One of the

plates D bears against each side of the railroad-rail, and said plates are provided with openings b^1 , through which pass the usual bolts, E, which extend through the shanks of the meeting ends of the rails, and thereby secure the same firmly between the plates D. Vertical bolts F pass through openings which are made 45 in the outer ends of the plates d^2 and in the flanges B, and thereby secure the plates D firmly on the tie against the possibility of lateral displacement.

A railway tie and chair thus constructed is 50 exceedingly strong and durable, and is adapted to secure the rails very firmly in place.

Having thus described my invention, I claim—

1. The rail-fastening device comprising the 55 plate D, bent to form the base-plate d^2 , having the lips or catches d^3 at its ends to engage the flanged edges of the tie, the lip D' , to embrace the base of the rail, and the vertical plate D^2 , to bear against the shank of the rail, substantially 60 as described.

2. The plates D, having the bases d^2 , provided with the lips or catches d^3 at their ends, the lips D' , and the vertical plates D^2 , for the purposes set forth, in combination with the 65 tie having the flanges B, and the rail or rails secured between the lips D' and plates D^2 of the plates D, substantially as described.

In testimony that I claim the foregoing as my own I have hereto affixed my signature in 70 presence of two witnesses.

ALFRED T. STEVENS.
